UNITED STATES PATENT OFFICE.

FRANK KOENIGKRAMER AND FREDERICK KOENIGKRAMER, OF CINCINNATI, OHIO.

SPRAYING APPARATUS.

No. 914,289.

Specification of Letters Patent.

Patented March 2, 1909.

Application filed July 17, 1908. Serial No. 444,134.

To all whom it may concern:

Be it known that we, FRANK KOENIGKRAMER and FREDERICK KOENIGKRAMER, citizens of the United States, residing at 5 Cincinnati, in the county of Hamilton and State of Ohio, have invented certain new and useful Improvements in Spraying Apparatus, of which the following is a specification.

Our invention relates to apparatus for 10 spraying white-wash, chemicals, and similar substances and mixtures.

One of its objects is to provide an apparatus adapted to be attached to an ordinary bucket or open tank and used for the above 15 purpose.

Another object is to provide simple, reliable and efficient mechanism for such purpose.

It further consists in certain details of 20 form, combination and arrangement, all of which will be more fully set forth in the description of the accompanying drawings, in which;

Figure 1 is a view, partly in side elevation, 25 and partly in section on line $w w$ of Fig. 3. Fig. 2 is a side elevation at right angles to that shown in Fig. 1, and with part of the tank shown broken away. Fig. 3 is a section on line $v v$ of Fig. 1. Fig. 4 is an enlarged central vertical section through the 30 pump cylinder and valves. Fig. 5 is a perspective view of the agitator blade, detached. Fig. 6 is a detail illustration of the attachment to an ordinary bucket.

We preferably provide a tank A of galvanized iron or enameled ware, to the upper edge of which is attached a channeled metal band a to reinforce the edge of the tank and form a means for firmly attaching the operative parts to the tank. If desired however, 35 the operative parts may be attached to an ordinary bucket A' having a wired rim a' as indicated in Fig. 6. The operative parts are carried by or mounted upon a frame B carried at or near the center of the tank, and 40 preferably slightly below the top edge of the tank in order that any liquid which may escape or drip from the operative parts will 45 flow back into the tank. The frame B is supported relative to the tank by means of radial arms b projecting from frame B, and 50 having downwardly projecting lugs b' . All

of the lugs b' may be provided with thumb bolts b^2 to engage the channel of the band a or beneath the rim a' . We prefer however 55 to provide inwardly projecting lugs b^3 on two of the arms b to engage the channel of band a or beneath the rim a' , while a thumb bolt on one arm b serves to draw the lugs b^3 into place and lock the frame B to the tank. 60 Either arrangement permits of readily attaching or detaching the frame B as required.

C represents the pump cylinder projecting downwardly from the frame B, and preferably formed integral therewith. The pump 65 cylinder is provided at its lower end with a screw plug c in which is mounted, preferably by threaded engagement, a valve cage c' , which cage carries a valve c^2 , the stem c^3 of which is locked to a limited movement by 70 means of a pin c^4 .

D represents a suction pipe projecting from the plug c down close to the bottom of the tank, in order that practically all the liquid may be drawn from the tank into the 75 pump.

E represents a plunger adapted to reciprocate within the pump cylinder, and is preferably packed with one or more leather cups. Any liquid which may pass to the top of 80 the plunger flows over the top of frame B and returns to the tank.

F represents the pump lever, which is pivoted at f to a standard f' carried by frame B. The pump lever is pivotally connected 85 to a rod G which is connected at its opposite end to the plunger E, whereby the operation of the pump lever serves to reciprocate the plunger in the pump cylinder. Attached to the rod G is an arm g passing down along side 90 the pump cylinder and carrying at its lowe end a blade or agitator g' , which has an opening g^2 for the passage of the suction pipe D, which serves as a guide for the same. The agitator serves to keep any finely divided 95 material suspended in the liquid in the tank.

H represents the outlet passage leading from the pump cylinder, this passage is preferably formed in a lug or projection h formed integral with the pump cylinder. 100

I represents a valve cage, preferably threaded into the upper end of passage H and provided with a valve i locked to the cage with a limited movement relative

- thereto by means of a pin i' through the valve stem. The valve cage I is provided with a wrench seat J and its upper end is threaded to receive a tee J' . An air chamber K is connected to the upper end of said tee and a flexible hose k is connected to the side of said tee, said hose being provided at its free end with a spraying nozzle k' and controlling valve k^2 . In order to prevent the plunger being withdrawn from the pump cylinder during the act of pumping, and to permit it being withdrawn when required for repairs, we provide a plate L attached to the frame B by a bolt, which serves to lock the plate L with its end l overhanging the pump cylinder to lock the plunger therein, and when the bolt is released the plate L may be shifted to permit the withdrawal of the plunger.
- 20 M represents a handle carried by the standard f' and adapted to be locked thereto by a set screw. The handle M serves as a convenient means for lifting the pump and tank when it is desired to carry the same from place to place.
- The above described arrangement of parts is simple and efficient, and permits ready access to all parts when required.
- 30 The apparatus herein shown and described is capable of considerable modification without departing from the principle of our invention.
- Having described our invention, what we claim is;
- 35 1. In a mechanism of the character indicated, a tank, a frame located within and slightly below the top edge of said tank and secured to said tank by radial arms having lugs engaging and locking said frame to the tank, a pump cylinder carried by and projecting downwardly from said frame, a plunger reciprocating within said cylinder, a pump lever carried by and above said frame, and suction and exit valves controlling the flow of liquid through said pump cylinder.
- 40 2. In a mechanism of the character indicated, a tank, a frame located over the central portion of said tank and secured thereto by radial arms having lugs engaging and locking said frame to the tank, a pump cylinder projecting downwardly from said frame, a plunger reciprocating within said cylinder, a pump lever carried by and above said frame, suction and exit valves controlling the flow of liquid through said pump cylinder, and a suction pipe projecting downwardly from said pump cylinder to near the bottom of said tank.
- 45 3. In a mechanism of the character indicated, a tank, a frame rigidly supported relative to said tank, a pump cylinder projecting downwardly from said frame into said tank, a discharge passage leading upwardly from said pump cylinder, a valve

cage provided with a discharge valve, said cage being threaded into said passage and threaded at its opposite end for connection with a hose and air chamber, an air chamber carried by and above said valve cage, and a flexible hose having connection between 70 said valve cage and air chamber.

4. In a mechanism of the character indicated, a tank, a frame rigidly supported relative to said tank by means of radial arms having lugs engaging and locking said frame 75 to the tank, a pump cylinder formed integral with and projecting downwardly from said frame into said tank, a pump lever carried by and above said frame, an agitator located within said tank and attached to and actuated by said pump lever, a discharge passage leading from said pump, an air chamber connected to said discharge passage, and a flexible hose connected to said discharge passage below said air chamber, and provided with 80 a spraying nozzle at its free end.

5. In a mechanism of the character indicated, a tank, a frame rigidly supported relative to said tank by means of radial arms having lugs engaging and locking said frame 90 to the tank, a pump cylinder formed integral with and projecting downwardly from said frame into said tank, a threaded plug closing the lower end of said cylinder, said plug carrying a downwardly projecting suction 95 pipe, a valve cage having threaded engagement with the upper end of said plug, and a suction valve seated within and having a limited movement relative to said valve cage.

6. In a mechanism of the character indicated, a tank, a frame rigidly supported relative to said tank, a pump cylinder projecting downwardly from said frame into said tank, a pump plunger located in said cylinder, a pump lever adapted to reciprocate said plunger carried by and above said frame, a suction pipe projecting downwardly from said cylinder, and an agitator guided by said suction pipe and reciprocated by the movements of said pump lever to agitate the liquid in said tank.

7. In a mechanism of the character indicated, a tank, a frame rigidly supported relative to said tank, a pump cylinder carried by and projecting downwardly from said frame into said tank, a plunger adapted to reciprocate within said cylinder, a pump lever and pump rod to reciprocate said plunger, and an adjustable member attached to said frame and adapted to project over the upper end of said pump cylinder to lock said plunger against accidental withdrawal from the cylinder.

8. In a mechanism of the character indicated, a tank, a frame rigidly supported relative to said tank, a pump cylinder carried by said frame, a suction valve, a downwardly projecting suction pipe, a discharge

passage leading from said cylinder, a valve
cage threaded at its lower end into said dis-
charge passage, a wrench seat exteriorly of
the center of said cage, and a threaded sec-
5 tion above said wrench seat to serve as a con-
nection for an air chamber and a flexible
hose.

In testimony whereof, we have affixed our
signatures in presence of two witnesses.

FRANK KOENIGKRAMER.
FREDERICK KOENIGKRAMER.
